MINE CAR BUFFER

Harold E. Abkowitz, Pittsburgh, Pa., assignor to
Pressed Steel Car Company, Inc., Pittsburgh,
Pa., a corporation of Pennsylvania

Application August 19, 1938, Serial No. 225,703
Renewed September 29, 1939

5 Claims. (Cl. 213—9)

This invention pertains to buffers, particularly those buffers applied to small cars such as mine and other industrial cars for absorbing draft and buffering shocks imposed upon the car. 5 This invention pertains more particularly to buffers of the foregoing type employing compression springs for absorbing the said shocks and more specifically to buffers in which the buffering shocks are transmitted to the springs 10 through the buffering block and the draft shocks transmitted to the springs by means of movement in the coupling pin independently of movement of the buffering block.

An object of the present invention is to provide 15 a buffer of the class described in which the same springs acting in compression absorb both coupling and draft shocks imposed upon the car.

Another object of the invention is to provide 20 a buffer of the class described in which independent mechanisms are provided for transmitting draft and buffering shocks imposed upon the said compression springs.

A further object of the invention is to provide 25 means in a buffer of the class described providing limited relative movement between the buffer and the means transmitting draft shocks to the springs, thereby tending to restrain lateral deflection of the said compression springs.

In the drawing forming a part of this specification 30 in which Fig. 1 shows a plan view of a portion of a car to which is attached the buffer embodying the invention; and Figs. 2, 3, 4, and 5 are sections taken on the lines 2—2, 3—3, 4—4, and 5—5 respectively of Fig. 1 and Fig. 6 is a 35 section on line 6—6 of Fig. 4 to illustrate details of construction, the reference character 1 indicates a portion of a car to which is adapted to be secured a buffer base 2 on which is mounted the buffering block 3 for movement longitudinally 40 of the car upon the base 2 when buffering shocks are imposed upon the buffering block and reference character 4 indicates the longitudinal sills of the car.

The buffer base 2 is constituted as a housing 45 for the hereinafter described compression springs and a support for the buffering block. This housing may take many forms. In some types of cars and particularly mine cars the base is attached directly to the floor and the longitudinal sills 50 of the car and constitutes the end sill of the car or that portion of the end sill disposed between the longitudinal sills. In other types of cars and some forms of mine cars an end sill is disposed between the longitudinal sills and the housing 55 2 is connected directly to the end sill. The par-

ticular mode of attaching the buffer base to the car structure forms no part of the present invention and the details of construction illustrated in the drawing as to this mode of attachment are not to be construed as limitations. 5

The base 2 shown in the drawing is of the form which constitutes the end sill of the car and includes a rear wall 5 constituting an abutment for the compression spring which wall is provided with suitable attachment flanges 6 and 10 7 for securing the base to the car structure. Extending outwardly from the rear wall 5 are top wall 8, bottom wall 9 and side walls 10 to form a hollow enclosure for reception of the compression springs and exclusion of dirt. The 15 top and bottom walls 8 and 9 preferably extend beyond the vertical plane of the side walls intermediate the side walls for connection to and support of the buffering block.

The buffering block comprises a buffering face 11 20 having rearwardly extending top wall 12, bottom wall 13 and side walls 14 enclosing corresponding walls of the base 2 and the top wall 12 of the buffering block rests on the top wall 8 of the base to provide support for the buffering 25 block. Upon reference to Fig. 1 of the drawing it will be noted that the base and buffering block combine to provide a telescoping wholly closed enclosure for the buffering springs and other hereinafter described mechanism. Mounted on the 30 top wall 12 of the buffering block and intermediate the side walls 14 is a suitable drawbar 15 disposed in spaced relation to the top wall 12 to provide space for admission of a coupling link between the drawbar and top wall 12 to be 35 engaged by the coupling pin. The drawbar 15 and top and bottom walls 12 and 13 respectively have suitably aligned apertures therein for reception of a coupling pin 16. These apertures are located rearwardly of the buffering face 40 11 and are elongated in a direction longitudinally of the car for a purpose hereinafter described.

Upon reference to Figs. 1 and 3 of the drawing 45 it will be noted that the coupling pin 16 engages only the drawbar and the buffering block and that the adjacent walls of the base 2 are offset to provide suitable clearance and avoid interference with the coupling pin as the buffering block moves toward and away from the base under imposed buffering shocks applied to the face 11 of the buffering block. Disposed between the top and bottom walls of the buffering block and extending rearwardly from the buffering face 11 on opposite sides of the coupling pin are spring 50 arm supports illustrated as vertically spaced 55

brackets 17. Pivots mounted on the brackets 17 by means of pivot pins 18 are spring arms 19 and 20 which have suitable apertures therein intermediate the ends thereof for reception of the pins 18. Each spring arm extends transversely of the buffering block on opposite sides of the pins 18 with their outer ends lying against the buffer face 11 of the buffering block, to provide a bearing cap for the compression springs and their inner ends suitably apertured for engagement with the coupling pin 16. Upon reference to Fig. 5 of the drawing it will be observed that the inner end of the spring arm 20 is bifurcated and the adjacent end of the spring arm 19 is disposed within the bifurcation and the whole engaged by the coupling pin 18. Disposed between the outer ends of each spring arm and the rear wall 5 of the base is a compression spring 21 having its opposite ends engaging the said rear wall and spring arm respectively.

Some means must be provided for connecting the buffering block and base to prevent separation thereof and at the same time provide relative movement therebetween upon compression of the springs 21. This may be readily accomplished by the insertion of removable pins through the respective top and bottom walls of both the buffering block and base and by elongating the apertures in one of the members to provide the relative movement between the members. To accomplish this purpose I prefer to use the pivot pins 18 of the spring arms and elongate the apertures in the top and bottom walls 8 and 9 respectively of the base 2. These pins 18 must of course be made removable when accomplishing this dual purpose so as to permit assembly and dis-assembly of the buffer.

Referring now to Fig. 1 of the drawing it will be observed that the compression springs 21 which extend between the wall 5 of the base and the buffering face 11 of the buffering block normally space said buffering face from the said rear wall and that the top and bottom walls of the base are spaced from the buffering face 11 a sufficient distance to permit relative movement of the buffering face toward and away from the said rear wall 5. During this described movement of the buffering block the pivot pins 18 move in the elongated apertures in the base 2 to permit the buffering block to move the spring arms 18 and 19 bodily towards the base 2 in compressing the springs 21. It will likewise be apparent upon reference to Figs. 1 and 2 that when cars embodying this buffer are coupled together and the coupling link pulls upon the coupling pin 16, the coupling pin can move within its elongated aperture in the buffering block independently of movement of the buffering block, thereby causing the spring arms 19 and 20 to rotate upon the pivot pins 18, which rotation is resisted by the springs 21, thus cushioning draft shocks imposed upon the coupling pin.

It will be noted upon reference to Fig. 1 of the drawing that the coupling pin is normally disposed adjacent the inner ends of its elongated aperture in the buffering block so that its mid-point is rearwardly of a line drawn through the centers of the pins 18. One purpose accomplished by so positioning the coupling pin is to obtain a quicker compression of the springs and reduce the amount which the buffering face 11 needs be spaced outwardly of the pins 18 to provide sufficient movement in the coupling pin to obtain compression of the springs 21, thereby reducing the necessary size of the buffering block

with the consequential saving in labor and materials.

Another object obtained by so positioning the coupling pin and making said rearward disposal of the coupling pin substantially equal to the amount the outer ends of the arms move in compressing the springs 21 and by elongating the apertures in the arms 19 and 20 which are engaged by the pins 18 is to obtain limited lateral bodily movement of the spring arms during movement of the coupling pin so that the force compressing the springs 21 is applied in substantially a straight line, thereby obtaining a direct compressive force upon the springs 21 instead of compression and bending normally resulting from a force applied at the end of a pivoted arm.

Having thus described the invention what I claim as new and desire to secure by Letters Patent is:

1. In a mine car buffer in combination, a base member for attachment to the car structure, a buffering block supported by said base member for movement relative thereto in absorbing buffering shocks, a coupling pin mounted in said buffering block for movement toward and away from said base independently of movement of said buffering block, spring arm pivot pins disposed on opposite sides of said coupling pin and mounted on said buffering block, elongated apertures in said base member through which said pivot pins extend, spring arms pivotally mounted intermediate their ends on said buffering block by means of said pivot pins, one end of each said arm pivotally engaging said coupling pin, the other end of each arm normally engaging said buffering block, and compression springs disposed between said latter ends of the spring arms and said base member to absorb draft and buffering shocks imparted to said coupling pin and buffering member.

2. In a mine car buffer, in combination, a base, a buffering block movable relative to said base under buffering shocks, compression springs disposed adjacent the sides of said buffering block and between said base and buffering block, a coupling pin, elongated apertures in said buffering block through which said coupling pin extends and providing relative horizontal movement between said block and said pin, spring arms mounted on said coupling pin and extending toward the sides of said buffering block, the free end of said arms being disposed between said compression springs and the front wall of said buffering block, means on said buffering block providing pivotal support for each spring arm intermediate the ends thereof, and pivot pins connecting said arms to said means and connecting said base and buffering block.

3. In a mine car buffer in combination, a base having top, bottom and side walls forming a hollow enclosure, a buffering block having a buffering face from which extends top, bottom and side walls enclosing the corresponding walls of said base, said buffering block being supported by said base and movable thereon under buffering shock imposed upon said buffering face, a coupling pin mounted on said buffering block and movable toward and away from said buffering face, compression springs disposed within said base and adjacent the side walls for absorbing buffering shocks imposed upon said buffering block, spring arms pivotally connected at one end to said coupling pin and having their free ends disposed between said springs and the buffering face of said buffering block, means on said buffering face extending between said top and bottom walls of said base to support each spring arm intermediate the ends thereof,

pivot pins connecting said spring arms to said spring arm supporting means.

4. A mine car buffer comprising a base having top, bottom and side walls, compression springs on said base disposed adjacent said side walls and extending beyond said top and bottom walls, a buffering block supported by said base and comprising a buffering face disposed across said springs and a rearwardly extending top wall adapted to 5 overlie the corresponding base wall, a coupling pin extending through said buffering block top wall and independently of said base, vertically disposed removable members connecting said base and buffering block on opposite sides of said coupling pin, spring arms pivotally connected to said coupling pin and pivotally mounted on said buffering block by means of said removable members, each said spring arm extending from said coupling pin to one of said springs and providing 10 a bearing for said spring against the buffering face of said block.

5. A mine car buffer comprising a base having top, bottom and side walls, compression springs on said base disposed adjacent said side walls and 15 extending beyond said top and bottom walls, a buffering block supported by said base and com-

prising a buffering face disposed across said springs and a rearwardly extending top wall adapted to overlie the corresponding base wall, a coupling pin extending through said buffering block top wall and independently of said base, vertically disposed removable members connecting said base and buffering block on opposite sides of said coupling pin, spring arms pivotally connected with said coupling pin and pivotally mounted on said buffering block by means of said removable members, each said spring arm extending from said coupling pin to one of said springs and providing a bearing for said spring against the buffering face of said block, each spring arm at said removable member having the aperture therein elongated 20 longitudinally of the arm providing limited movement of the arm longitudinally of said buffering face and each wall of the said base at said removable member having the aperture elongated in a direction normal to said buffering face for reception of each said removable member providing relative movement between each said removable member and said base during movement of the buffering block.
